UNITED STATES PATENT OFFICE.

JOHN DUDE, OF SALT LAKE CITY, UTAH, ASSIGNOR OF ONE-HALF TO HOWARD S. BROWN, OF OASIS, UTAH, AND ONE-FOURTH TO SAMUEL W. STEWART, OF SALT LAKE CITY, UTAH.

EXCAVATING WHEEL.

Application filed May 26, 1921, Serial No. 472,735. Renewed March 24, 1923.

To all whom it may concern:

Be it known that I, JOHN DUDE, a citizen of the United States, residing at Salt Lake City, in the county of Salt Lake and State of Utah, have invented certain new and useful Improvements in Excavating Wheels; and I do declare the following to be a full, clear, and exact description of the invention, such as will enable others skilled in the art 10 to which it appertains to make and use the same.

This invention relates to an improved excavating wheel for use in digging ditches and one object of the invention is to provide 15 an improved excavating wheel having an improved construction in the bucket and to particularly provide improved doors and means for releasably holding the doors in a closed position.

Another object of the invention is to so construct this wheel that the doors may be securely held in a closed position when desired but permitted to easily move to an open position when a bucket is in the proper 25 position for dropping the contents of the bucket onto a conveyor belt.

Another object of the invention is to provide type of scraper for emptying the contents from the bucket.

Another object of the invention is to so construct and mount the doors of the bucket that after being moved to an open position, the doors will of their own weight move to a closed position as the wheel continues to rotate and the bucket moves downwardly into a trench.

Another object of the invention is to provide an excavating wheel in which the bucket will be strong and durable and of a 40 simple construction.

This invention is illustrated in the accompanying drawings, wherein:

Figure 1 is a view showing the improved excavating wheel in vertical section and in 45 position for use.

Figure 2 is an enlarged fragmentary view showing a portion of the wheel in elevation.

Figure 3 is a top plan view of the structure shown in Fig. 1.

Figure 4 is a fragmentary top plan view 50 showing the doors open.

Figure 5 is a sectional view taken along the line 5—5 of Fig. 2.

Figure 6 is a transverse sectional view through a bucket with the scraper shown in 55 elevation.

This improved excavator is of the wheel type and includes a frame having side bars 1 which support hanger frames 2, it being understood that there will be provided two 60 of these side bars 1 and each of them will support a frame 2. Supporting rollers 3 are carried by the hanger frames 2, the rollers being mounted by a shaft 4 and one or more of the rollers being provided with sprocket 65 teeth so that rotary movement may be transmitted to the wheel as will be hereinafter brought out.

The wheel is provided with side rings 5 which are positioned between the side bars 70 1 and about the hanger frames 2 and carry toothed rings or sprocket rings 6 which will be in intermeshing engagement with the driving sprockets. It will thus be seen that since the rings are rotatably mounted by 75 means of the rollers 3 and the sprocket teeth mesh with the teeth of certain of these rollers, that rotary movement can be transmitted to the rings when power is applied to the shaft carrying the sprocket wheel.

The buckets are carried by side rings 5 and each is provided with an open-ended body portion 7 formed of heavy sheet metal and having its side portions overlapping the side rings 5 and secured to the same by rivets or other suitable fasteners. Cutting teeth 8 are secured to the outer face of the bucket and have their end portions extending beyond the end of the bucket and bent to extend as shown so that these teeth will cut 90 into the ground as the wheel rotates. It will thus be seen that with the wheel in position and rotating, the teeth will cut into the breast portion of the trench and the dirt scraped and cut loose by the teeth will fall 95 into the buckets.

Each bucket is provided at its rear end with doors 9 which are carried by hinge bars 10, the hinge bars 10 being pivotally mounted as shown at 11 and provided with arm extensions 12 braced by diagonally extending braces 13. The doors will therefore be pivot-

ally mounted at the rear end of the bucket and will be so balanced that after the doors have been swung to an open position and continued rotation of the wheel moves a bucket downwardly into the trench, the doors will of themselves swing to the closed position. When the bucket is moving upwardly, the weight of the doors and the weight of dirt scraped into the bucket would cause the doors to swing open but in order to prevent this, there has been provided arcuate strips 14 which are suitably supported from the side bars 1 and extend from a point adjacent the bottom of the trench to a point adjacent the upper portion of the wheel but somewhat short of the uppermost point of this wheel.

In order to provide a bottom for the buckets, there has been provided an arcuate strip 15 which is supported from the depending frames 2 as shown at 16 and is of substantially the same lengths as the strips 14. At the upper end of this bottom strip 15, there has been secured a plate 17 which constitutes a chute and extends downwardly over an endless conveyor 18 which extends through the wheel and is adapted to receive dirt from the buckets and carry the dirt to a suitable point of delivery. A support 19 is carried by one of the side bars of the conveyor and carries a scraping blade 20 which is in the form of a strip of heavy sheet metal. This scraping blade or plate 20 is braced by bracing bars 21 which are formed of angle iron and supported from the side bars 1 within the wheel as shown at 22. The scraping blades and bars 21 are further braced by a plate 23 which is secured between the angle bars 21 and cut on the arc of a circle to give added strength to this plate. It will thus be seen that this excavating wheel will be simple in construction but at the same time very strong and durable.

When this wheel is in use, it is mounted as shown and as the wheel rotates, the bucket will first move down into the trench and will then move upwardly with the teeth 8 cutting and scraping into the breast of the trench. The dirt cut and scraped loose by these teeth will fall into the bucket and will be held in this bucket since the bucket is by this time moving longitudinally of the bottom strip 15 and the arms of the doors are in engagement with the side strips 14. When the bucket reaches the end of the bottom strip 15 and the arms move out of engagement with the side strips 14, the scraping blade or plate 20 will have entered the open forward end of the bucket and any dirt which has not of itself fallen onto the chute 17 and moved down this chute onto the endless conveyor will be scraped loose. If clay or other sticky material is being excavated and would have a tendency to remain in a solid cake this

solid cake would be forced rearwardly of the bucket and the doors would be moved to an open position thus permitting the cake to be forced out of the bucket and drop down onto the conveyor. Opening movement of the doors is limited since the doors will engage the rings 5 and therefore cannot move outwardly beyond the position shown in Fig. 4. As soon as the bucket moves out of engagement with the scraper and starts to move downwardly, the doors will be left free to close and upon continued downward movement of these doors, the doors will of their own weight swing inwardly to a closed position where they will remain. It will thus be seen that the scraper is so constructed that it may thoroughly scrape the dirt and caked clay out of the bucket and that the doors are so mounted that the doors may be swung to an open position by pressure of caked clay or by the action of the scraper moving rearwardly through the bucket. It will be further noted that the excavating wheel is so constructed that the doors will of themselves swing to a closed position and that improved means has been provided for retaining the doors in a closed position while the buckets are being filled and until the buckets reach the proper position for emptying.

I claim:

1. In an excavator, a rotatable wheel having spaced side rings, open ended buckets carried by the side rings, a stationary bottom strip extending between the side rings adjacent their inner peripheries for a portion of the circumference of the wheel, side strips extending circumferentially of the wheel and conforming to the position and length of the bottom strip, doors for the rear ends of the buckets hingedly mounted at the sides for opening outwardly and provided with lever arms extending for engaging said side strips and holding the doors closed while the buckets are moving upwardly along the bottom strip, and a scraper for passing through the buckets, the arms moving out of engagement with the side strips and the doors moving to an open position as the scraper passes through the buckets, and the rings limiting outward movement of the doors.

2. In an excavating device, a rotatable wheel including spaced side rings, open ended buckets carried by the wheel, stationary side strips extending partially about the wheel, a stationary bottom strip for the buckets extending partially about the wheel in conformity to the length and position of the side strips, pivot pins carried by the side rings of said wheel adjacent the rear ends of said buckets and extending outwardly, doors for the buckets pivotally mounted by said pins for swinging transversely of the buckets and wheel and each provided with an

arm, extending rearwardly of the bucket wheel, and a scraper at the point of discharge for passing through the buckets and side strips engaging the arms of the doors to hold the doors closed until the buckets reach the point of discharge and said doors being limited in their opening movement by engagement with the spaced rings of said

charge for passing through the buckets and moving the doors outwardly to an open position. 10

In testimony whereof I have hereunto set my hand.

JOHN DUDEK.
